Primary Examiner—Philip S Hyder*Assistant Examiner*—Susan E Krakower(74) Attorney, Agent, or Firm—Crowell & Moring LLP(57) CLAIM

The ornamental design for a portion of an article of clothing, as shown and described.

DESCRIPTION

This application is related to the following co-pending application:

Application Ser. No. 29/317,898, entitled “Decorative Element for a Vehicle or Part Thereof”.

The FIGURE is a front view of a portion of an article of clothing according to our novel design.

The Examiner understands the claim is a 2-Dimensional surface ornament to be applied to an article of clothing.

The broken lines illustrate environmental structure and form no part of the claimed design.
